(57) **CLAIM**

The ornamental design for a sander tool with pivoting handle, as shown and described.

DESCRIPTION

FIG. 1 is a perspective view of a sander tool with pivoting handle showing our new design;

FIG. 2 is a top plan view thereof;

FIG. 3 is a front elevational view thereof;

FIG. 4 is a right side elevational view thereof; and,

FIG. 5 is a perspective view of a sander tool showing an alternate position of a pivot pole connector.

The left side elevation view is not shown as it is identical to the right side elevational.

The rear elevational view of the sander tool is identical to the front elevation, and thus is not shown.

The bottom plan view is not shown as the bottom of the sander tool is planar and has no distinguishing ornamental features.

The broken line showing of the pole in FIG. 5 is included for the purpose of illustrating environmental structure and forms no part of the claimed design. The broken line showings of the various details form no part of the claimed design.
